Application February 18, 1947, Serial No. 137,008

Term of patent 7 years

(Cl. D33—1)

To all whom it may concern:

Be it known that I, Herbert M. Rothschild, a citizen of the United States, residing at Kitchawan, in the county of Westchester and State of New York, have invented a new, original, and ornamental Design for Furniture Base Unit, of which the following is a specification, reference being had to the accompanying drawing, forming part thereof.

Fig. 1 is a perspective view of the furniture base unit; Fig. 2 is a side elevation of the base unit shown as supporting the ends of a box spring and mattress indicated in dotted lines for illustrative purposes only; and Fig. 3 is an end elevation of the base unit.

I claim:

The ornamental design for a furniture base unit, as shown and described.

HERBERT M. ROTHSCHILD.
